UNITED STATES PATENT OFFICE

102,975

DESIGN FOR A TYPEWRITING MACHINE

James H. Rand, Jr., and Russell E. Benner,
Buffalo, N. Y., assignors to Remington Rand
Inc., Buffalo, N. Y., a corporation of Delaware

Application December 26, 1935, Serial No. 60,294

Term of patent 7 years

To all whom it may concern:

Be it known that we, James H. Rand, Jr., and Russell E. Benner, citizens of the United States residing in Buffalo, in the county of Erie and State of New York, have jointly invented a new, original, and ornamental Design for a Typewriting Machine, of which the following is a specification, reference being had to the accompanying drawing forming part thereof and in which:—

Fig. 1 is a perspective view of a typewriting machine showing our design, the view showing the machine as it appears when viewed from the front thereof.

Fig. 2 is a side view of the machine.

The characteristic features of the design are included more particularly in the cover plate A of the machine and comprise a smooth surfaced angular rim *a* and a body portion *b* which is curved from the rim *a* to the edge *c*, presenting no straight lines as it is viewed from the front of the machine and except for the angular rim having a crackle finish throughout.

We claim:

The ornamental design for a typewriting machine, as shown and described.

JAMES H. RAND, JR.
RUSSELL E. BENNER.
